(57) **CLAIM**

The ornamental design for a freezer array, as shown and described.

DESCRIPTION

FIG. 1 is a top isometric view of a freezer array embodying our new design;

FIG. 2 is a top plan view of the freezer array;

FIG. 3 is a front orthographic view of the freezer array;

FIG. 4 is a rear orthographic view of the freezer array;

FIG. 5 is a right side orthographic view of the freezer array,

the left side is a mirror image thereof; and,

FIG. 6 is an enlarged partial perspective view of one of the corners of the freezer array showing more detail.
